[57] CLAIM

The ornamental design for a tab for food container lid, as shown and described.

DESCRIPTION

FIG. 1 is a top right front perspective view of a tab for food container lid showing my new design. The broken lines are for illustrative purposes only and form no part of the claimed design;

FIG. 2 is a front elevational view thereof;

FIG. 3 is a top plan view thereof;

FIG. 4 is a right side elevational thereof; the left side elevational view being a mirror image;

FIG. 5 is a bottom plan view thereof; and,

FIG. 6 is a rear elevational view thereof.

The broken line showing of a lid portion in FIGS. 1 through 6 is for illustrative purposes only and forms no part of the claimed design.
